UNITED STATES PATENT OFFICE.

SAMUEL A. NEIDICH, OF EDGEWATER PARK, NEW JERSEY, ASSIGNOR TO THE AMERICAN MULTIGRAPH COMPANY, OF CLEVELAND, OHIO, A CORPORATION OF OHIO.

LITHOGRAPHIC PLATE.

1,203,770.

Specification of Letters Patent.

Patented Nov. 7, 1916.

Application filed August 22, 1914. Serial No. 858,012.

To all whom it may concern:

Be it known that I, SAMUEL A. NEIDICH, a citizen of the United States, residing at Edgewater Park, in the county of Burlington, ton and State of New Jersey, have invented a certain new and useful Improvement in Lithographic Plates, of which the following is a full, clear, and exact description, reference being had to the accompanying drawings.

This invention relates to lithographic plates of such a character that they may have the work or image firmly affixed thereto by a minimum amount of labor and skill, and, when so prepared, will be very efficient and extremely durable in service. My plate, before the work is applied, has its entire face ink-resisting, when moist, but adapted to hold at any desired place an adhering ink-receiving substance. The extreme desirability of such a plate will be best understood by contrast with the troublesome working requirements of ordinary plates.

In the ordinary processes of preparing metal lithographic plates for printing, a grained plate has the work or image applied direct to it in some greasy medium and thereafter the balance of the plate is etched and gummed to make it ink-resisting when

moist. In such old processes it is very important that no grease be present on the grained plate where printing is not desired, and that the plate be kept free from oxidation, and great skill is required, as well as considerable time, in accomplishing the etching. Inasmuch as the etching operation tends to remove the work, the usual method has been to partially etch the plate and thereafter strengthen the work and then further etch the plate and further strengthen the work, if necessary. These successive operations require great skill and caution, lest the work be partially removed by the etching substances. There is great liability of spoiling the plate during this process, for, if the etching removes the least part of the work, the plate is ruined, or is only preserved by tedious subsequent operations. Unless the operation is carried out with the greatest possible care, the plate lacks durability, as the image is liable to become partially removed during the operation of the printing. Furthermore, the work as ordinarily prepared upon the plate, is soluble in

all the ordinary solvents for ink, and, should ink accidentally be permitted to dry on the face of the plate, it is difficult of removal without also removing the work.

My applications Nos. 856,201 and 856,202, filed August 11th, 1914, describe and claim processes of producing, ready for printing, lithographic plates which are preetched over the entire surface of the plate and have the work applied thereto after etching. These applications describe two methods of applying the work to the preetched plate, namely; in No. 856,201 a waxy image is secured directly to an ungummed preetched plate by heat. In application No. 856,202, the usual gum arabic solution is used with the etching of the plate and to the gummed and dried plate is applied the image by means of a hard emulsified wax and a substance like bichromate of ammonium, which, when heated, coact with the gum and produce a dry compound of wax and bichromated gum carrying the image. The emulsified wax may be carried either by the image-applying solution or may be incorporated with the gum of the plate,—in the latter instance, the wax, at the places where there is no image, washing off with the gum arabic.

It will be seen that in each instance the plate is etched over its entire face preliminary to the work being applied, and thereafter the work is applied, as desired, on an etched surface. By such a process I do away with the element of skill in the etching operation, as I am not hampered by the presence of any work on the plate. I very materially shorten the time required, since I can use the strongest etching solution and accomplish it at one time instead of by several successive operations. The plate is not liable to be spoiled by reason of ink inadvertently drying on the surface, for at any time such ink may be dissolved off without affecting the work. Finally, my plate is more permanent, both in its ink-carrying and ink-resisting properties.

Inasmuch as the etching of my plate is entirely independent of the character of the work to be produced, it is possible to perform the etching as a manufacturing operation, in conjunction with the graining of the plate, and to supply to users ready-etched plates having wonderfully greater

keeping qualities than the usual grained plates, as well as free from the possibility of damage from accidental grease deposits or from oxidization. Chemical manipulation of the plate—by the users—is therefore eliminated, as he is only required to apply the image to the plate and secure it by heating.

The present application relates to the pre-
10 etched plate itself, which may be used in carrying out lithographic operations, of which those described are examples. This plate may be briefly summarized as a new article of manufacture, comprising a plate
15 chemically prepared for lithographic purposes and capable, when moist, of resisting ink over its entire surface and capable of having an ink-receiving image adhere to it, whereby it becomes an effective lithographic
20 printing plate.

The plate of this invention may be of any suitable metal. I have found zinc well adapted for the purposes. The zinc plate is first mechanically grained in the ordinary
25 manner and is then etched over its entire face before any work is applied. This etching may be accomplished by usual etching solutions, though I prefer to use a strong solution to save time.

30 After my plate is etched it may be preserved indefinitely; it does not deteriorate in use and is not liable to be spoiled by greasy thumb marks, etc. If the plate is intended for use according to the process of
35 my application No. 856,201 wherein a waxy image is applied to the plate directly by heat, the plate, as a stock article, needs no further treatment. If, however, I wish to produce a plate adapted for conveniently
40 carrying out the process of my application No. 856,202, I employ, with the etching solution, the usual gum arabic solution, so that the plate is not only preëtched over its entire face, but is gummed as well. In one
45 method of carrying out the process of the latter application, I incorporate with the gum arabic solution emulsified carnauba wax, instead of using such emulsion in the work solution itself. Accordingly, the present invention includes a grained preëtched plate; second, such a plate gummed over its
50 face; and third, such a plate gummed and carrying emulsified wax.

My plate is illustrated diagrammatically
55 in the drawings hereof, in which—

Figure 1 is a vertical section through the grained and etched plate on a very much enlarged scale. For graphic representation, the etching is shown as surmounting the grain, though, in actual practice it is incorporated with it. Fig. 2 shows the plate of Fig. 1 with a surmounting coat of gum. Fig. 3 shows the plate with an image applied above the gum. Fig. 4 is a plan of
60 the plate shown in Fig. 3.

Referring to the drawings by reference characters, A indicates a plate of zinc, or other metal, and *a* the graining thereon.

B represents the etching, C the gum coat which may or may not contain emulsified wax, and D the work or image.

As above described, the plate shown in the drawings is prepared by taking a plate of zinc, aluminum or other suitable metal, graining it, as in the ordinary lithographic process, and etching the entire face thereof very completely, so as to make a thoroughly ink-resisting surface. For these purposes I may use any of the well-known etching compounds, preferably a comparatively strong compound. For producing the plate shown in Figs. 2 and 3 of the drawings, in addition to etching the plate, I gum it and drum the gum. Where it is desired to incorporate in the gum an emulsified hard wax, as above referred to, this may be conveniently accomplished by mixing with the gum arabic solution an emulsion of carnauba with water of such proportions that the final mixture will contain approximately equal quantities of solid gum arabic and solid carnauba wax, the latter in suspension. The emulsified carnauba may be obtained on the market as an emulsion, or may be emulsified by employing amidduron or stearamid (*i. e.*, the amid of stearic acid, $C_{17}H_{35}CONH_2$), which is on the market for such purposes.

Whether my preëtched plate is used without the gum solution and has the wax image applied thereto by heat, or is used with the gum solution and has the image applied in the form of a bichromate solution with wax and thereafter heated, or is used with gum and wax incorporated with a plate and has the image applied simply as a bichromate solution affixed by heat—in any case, the plate is characterized by having its entire face etched previous to the application of any work to the plate.

Having thus described my invention, what I claim is:

1. As a new article of manufacture, a metallic plate adapted for lithographic purposes and capable when moist of resisting ink over its entire face sufficiently for lithographic printing without subsequent chemical treatment and capable of having an ink-carrying image affixed firmly to it.

2. As a new article of manufacture, a metallic lithographic plate etched over its entire face sufficiently to be workable when moist as an ink-repellent surface without further chemical treatment and adapted to receive a design thereon.

3. As a new article of manufacture, a metallic lithographic plate grained and etched over its entire face, to be ink-resisting sufficiently for lithographic printing when moist without further chemical treatment.

4. As a new article of manufacture, a me-

125

120

130

tallic lithographic plate etched to be ink-resisting sufficiently for lithographic printing when moist, and gummed over its entire face.

5 5. As a new article of manufacture, a metallic lithographic plate grained, etched to be ink-resisting sufficiently for lithographic printing when moist and gummed over its entire face.

10 6. As a new article of manufacture, a plate adapted for lithographic purposes consisting of a metal plate grained over its entire face and etched over the entire face over the graining, and gummed over its entire

15 face.

7. As a new article of manufacture, a metallic lithographic plate etched over its entire face and gummed, the gum containing wax.

20 8. As a new article of manufacture, a lithographic plate grained, etched and

gummed over its entire face, the gum containing emulsified wax.

9. As a new article of manufacture, a plate adapted for lithographic purposes consisting of a metal plate etched over its entire face, and gummed over its entire face, the gum containing emulsified carnauba wax.

10. As a new article of manufacture, a plate adapted for lithographic purposes consisting of a metal plate grained over its entire face and etched over the entire face, and gummed over the entire face with a solution of gum arabic containing emulsified carnauba wax.

In testimony whereof, I hereunto affix my signature in the presence of two witnesses.

SAMUEL A. NEIDICH.
